UNITED STATES PATENT OFFICE.

FRANCIS G. DAVIS, OF WATERTOWN, NEW YORK, ASSIGNOR TO THE H. H. BABCOCK COMPANY, OF SAME PLACE.

DESIGN FOR AN AMBULANCE-BODY.

SPECIFICATION forming part of Design No. 29,392, dated September 20, 1898.

Application filed August 19, 1898. Serial No. 689,022. Term of patent 7 years.

To all whom it may concern:

Be it known that I, FRANCIS G. DAVIS, a citizen of the United States, residing at Watertown, in the county of Jefferson and State of New York, have invented and produced a new and original Design for an Ambulance-Body, of which the following is a specification, reference being had to the accompanying drawing, forming a part thereof.

This design relates to the configuration of the body of an ambulance.

The accompanying drawing is a side elevation of an ambulance embodying my design.

The leading feature of my design is the side outline of the body, which extends from the front end of the roof in a curved line backwardly and downwardly, then straight downwardly, then in a curved line downwardly and forwardly to the level of the bottom of the front portion of the body, which contains the driver's seat, then backwardly in about a horizontal direction, then downwardly for a short distance to the front end of the main bottom, which is arranged at

a lower level than the bottom of the front 25 portion, then horizontally rearwardly to the rear end of the main bottom, then upwardly to the rear end of the roof, and then forwardly to the front end of the roof.

Referring to the drawing, A represents the 30 roof; B, the front portion of the body, containing the driver's seat; b, the bottom of this front portion; c the vertical part, and c' the 35 upper and c² the lower curved parts of the front edge of this front portion, and D the main bottom, which is arranged at a lower level than the bottom of the front portion B and which extends horizontally to the rear end of the body.

What I claim is—

The design for an ambulance-body, substantially as herein shown and described.

Witness my hand this 15th day of August, 1898.

FRANCIS G. DAVIS.
